To all whom it may concern:

Be it known that I, MATILDA R. LITTELL, a citizen of the United States, residing at New York, in the county and State of New York, have invented and produced a new and original Design for Lamp or Candle Shades, of which the following is a specification.

The essential feature of my new and original design comprises in a lamp or candle shade an unconventional decoration in relief upon the outer surface of the shade.

The drawing illustrates in perspective a lamp-shade embodying my design.

Referring to the drawing, A designates a

I claim as new and original—

The design for a lamp or candle shade substantially as herein shown and described.

In testimony whereof I affix my signature in the presence of two witnesses.
